UNITED STATES PATENT OFFICE.

JOHN F. ROBERTSON, OF BELLEVUE, PENNSYLVANIA.

OIL-PURIFIER.

1,223,423.

Specification of Letters Patent. Patented Apr. 24, 1917.

Application filed June 6, 1916. Serial No. 101,953.

To all whom it may concern:

Be it known that I, JOHN F. ROBERTSON, a citizen of the United States, and resident of Bellevue, in the county of Allegheny and State of Pennsylvania, have invented a new and useful Improvement in Oil-Purifiers; and I do hereby declare the following to be a full, clear, and exact description thereof.

My invention relates to an oil purifier or filter, the object of my invention being to provide a compact apparatus of this character which is simple in construction, and in which large quantities of oil can be purified rapidly while, at the same time, the parts are accessible and capable of removal for purposes of cleaning or repair, and without interruption to the general operation of the filter.

My invention comprises the novel features hereinafter set forth and claimed.

In the accompanying drawings, Figure 1 is a side elevation, partly broken away, of my improved filter; Fig. 2 is a plan view with top removed; Fig. 3 is an enlarged section on the line 3—3, Fig. 2; and Fig. 4 is an enlarged section on the line 4—4, Fig. 2.

In the drawings, the numeral 2 designates a suitable casing made up of plates of metal of proper thickness and united to form a strong rigid structure. Within the casing 2 is the reservoir 3 to receive the dirty oil. The oil is delivered to the reservoir 3 through the inlet-pipe 4 provided at its upper end with the strainer 5. This inlet-pipe 4 extends down within the tank to the lower end thereof, or what may be termed "the settling compartment" 6.

The reservoir 3 is provided with the steam-jacket 7, which may extend only for a portion of the height of said reservoir within the zone containing the oil, and this steam-jacket is supplied with steam from the steam inlet-pipe 8.

The pipe 9 extends down within the reservoir 3, said pipe having the connections 10, 11 and 12, with the pipes 13, 14 and 15 connected to said connections, respectively, and said pipes being provided with the valves 16.

These pipes 13, 14 and 15 deliver the oil rising in the pipe 9 to the pans 17, 18 and 19, respectively. These pans rest upon suitable supports 20 and are arranged to slide in and out on said supports so that the pans may be removed independently of each other, as more fully hereinafter set forth.

The pans are provided with steam-jackets

21 supplied with steam from the pipe 22, which is connected up with the steam-pipe 23 from the steam-jacket 7 of the reservoir 3. Valves 24 are provided to control the supply of steam to the steam-jackets of the different pans.

The interiors of the pans are provided with the baffles 25 extending in opposite directions and overlapping each other, as indicated in Fig. 1 so that the oil on entering the pan at one end is compelled to pass in a tortuous course from one end of the pan to the other, giving the sediment and foreign matter in the oil an opportunity to settle before the oil finally escapes by the outlet-pipes 26. These outlet-pipes discharge the oil into the filter bags 27 whence the oil drips from said bags into the clean-oil compartment 28.

This clean-oil compartment has the cooling coil 29 arranged in the bottom thereof to cool the oil and clean oil is drawn off through the outlet 30 controlled by the valve 31. The water to the cooling coil is supplied through the inlet 32.

A pipe 33 extends down into the settling compartment 6 of the reservoir 3, said pipe having at its upper end the elbow 34, which projects out through an opening in the reservoir, and has the movable spout 35 connected thereto. This spout delivers into the funnel 36 at the upper end of the drain pipe 37, leading to the drain 38. The water mixed with the dirty oil will settle in the settling compartment, being heavier than the oil and will rise within the ejector-pipe 33, being forced up therein by the weight of the oil.

Goose-necks 39 leading from the steam-jackets of the pans carry off the condensation, which is delivered into the waste-pipe 40.

The casing 2 is provided with the doors 41 by which access is had to the pans, and with a door 42 by which access is had to the filter-bags.

The dirty oil is introduced into the pipe 4, passing through the strainer 5 and down through said pipe into the lower end of the reservoir 3. The oil will rise in the reservoir, the water, as stated, settling to the bottom and being forced up through the pipe 33 to the drain. As the oil rises in the reservoir 3, it is heated by the steam-jacket 7 and a portion of the dirt or foreign matter will settle in the lower end of the reservoir to be

drawn off from time to time by the waste-pipe 44. As the oil rises in the reservoir, it will enter the pipe 9 and will be carried off by the pipes 13, 14 and 15 to the pans 17, 18 and 19, respectively. The oil discharged into the pans is retarded in its flow by the baffles and is compelled to take a tortuous course, which permits of the deposit of the dirt in the pans while, at the same time, the oil is heated by the steam-jackets, and this further aids in the deposit of the dirt. The oil finally passes by the pipe 26 into the filter-bags 27 and thence down into the clean-oil compartment to be drawn off by the pipe 30.

When it is desired to remove one of the pans for purpose of cleaning, or for other reason, the steam-pipe connection to the water-jackets is disconnected, and the pan can then be readily removed by withdrawing it. It should have been stated that the valve 16 is first closed so as to prevent the discharge of the oil from the pipe 15. The pan in this manner is removed and cleaned or repaired as the case may be, and is then re-inserted in its proper position and the steam-pipe connected thereto, whereupon it is ready for further treatment of the oil. In this manner, I provide for the removal of the pans independently of each other, and, by having them arranged in the manner described, this is effected without disturbing the operations in the other pans and, in this manner, the filter operates continuously even though one or more of the pans may be out of operation.

By my apparatus, I provide for the cleaning of a greater quantity of oil in less time while, at the same time, the apparatus is very compact and, due to the heating of the oil by the steam-jackets, the operation of cleaning the oil is rendered very much more effective and more rapid thereby decreasing the cost and giving a greater saving in oil.

45. What I claim is:

1. In an oil purifier, the combination with a suitable frame, of a reservoir for containing the impure oil, a plurality of settling-pans supported in said frame, means for delivering the oil from said reservoir to said pans, and means for removing said pans independently from said frame.

2. In an oil purifier, the combination with a suitable frame, of a reservoir for the impure oil, a plurality of settling-pans mounted in said frame one above the other, means for delivering the oil from said reservoir to said pans, and means for removing said pans independently from said frame.

3. In an oil purifier, the combination with a suitable frame, of a reservoir for the impure oil, a plurality of settling-pans mounted one above the other in said frame, means for delivering the oil from said reservoir to said pans, and means for withdrawing said pans horizontally from said frame the one independently of the other.

4. In an oil purifier, the combination with a suitable frame, of a reservoir for the impure oil, a plurality of settling-pans mounted therein, independent means for delivering the oil from said reservoir, and means for removing said pans from said frame independently.

5. In an oil purifier, the combination with a suitable frame, of a reservoir for the impure oil, a steam-jacket surrounding said reservoir, a plurality of settling-pans mounted in said frame one above the other, means for delivering the oil from said reservoir to said pans, and means for removing said pans independently.

6. In an oil purifier, the combination with a suitable frame, of a reservoir for the impure oil, a pipe extending down into said reservoir, a plurality of settling-pans mounted in said frame one above the other, connections from said pipe to each of said pans.

7. In an oil purifier, the combination with a suitable frame, of a reservoir for the impure oil, a pipe extending down into said reservoir, a plurality of settling-pans mounted in said frame one above the other, valve-controlled connections from said pipe to each of said pans.

8. In an oil purifier, the combination with a suitable frame, of a reservoir for the impure oil, a plurality of settling-pans one above the other mounted in said frame, means for delivering the oil from said reservoir to each of said pans, an overflow pipe leading from each of said pans, and a filter-bag communicating with each of said overflow pipes.

9. In an oil purifier, the combination with a suitable frame, of a reservoir for the impure oil, a plurality of settling-pans mounted in said frame one above the other and independently removable therefrom, means for delivering the oil from said reservoir to each of said pans, and a reservoir for the pure oil overflowing from said settling-pans.

In testimony whereof I, the said JOHN F. ROBERTSON, have hereunto set my hand.

JOHN F. ROBERTSON.
